UNITED STATES PATENT OFFICE.

HARRY M. NOBIS, OF EAST CLEVELAND, OHIO.

HUMIDIFIER FOR FURNACES.

Application filed January 23, 1923. Serial No. 614,406.

To all whom it may concern:

Be it known that I, HARRY M. NOBIS, a resident of the city of East Cleveland, county of Cuyahoga, and State of Ohio, and a citizen of the United States of America, have invented certain new and useful Improvements in Humidifiers for Furnaces, of which the following is a specification.

This invention I term a humidifier and relates to mechanical attachments for furnaces whereby moisture is supplied to the air for circulation through buildings to be heated. The attachment herein described is designed especially for hot air furnaces and 15 is arranged to be detachably mounted upon the dome of the furnace whereby the heated air rising about the fire chamber will be moistened by evaporation from the water exposed thereto as the latter is fed into the air 20 chamber by said attachment.

It is an object of this invention to provide a humidifier for the above purpose which shall supply an especially large surface of liquid for evaporation, and to provide means 25 for controlling the rate of flow of the liquid used over said humidifier, the amount of evaporation depending, of course, upon the heat of the furnace, the amount of moisture surface exposed and the draft of air in circulation therethrough.

It is a further object of my invention to provide the liquid holder which I use in the form of an open, spiral, trough-like groove for receiving liquid therein at one end at 35 the top-most point of said groove, to provide means for feeding liquid from a source of supply outside the furnace to the highest point of the spiral, and for draining off any surplus or overflow liquid which may flow 40 from the lowest point of the spiral.

It is a special advantage of my humidifier that it is easily mounted upon the usual type of hot air furnaces, and can be detached and thereby readily removed therefrom 45 when desired for any reason. It is also easily cleaned or repaired, if it should be necessary, and can therefore be readily replaced by another.

My invention therefore consists of an 50 attachment which is relatively inexpensive, simply constructed and easily operated. The parts thereof are arranged and constructed as hereinafter more particularly described.

and pointed out in the appended claims, reference being had to the accompanying drawings in which:—

Figure 1 represents the upper part of a hot air furnace, a part being broken away to show my attachment as applied thereto;

Figure 2 represents a central vertical section of the humidifier, as shown in Fig. 1;

Figures 3 and 4 are elevational and plan views, respectively, of a modified form of humidifier;

Figure 5 is a vertical section of a drip cup device and tube leading therefrom, as used in either form of humidifier; and

Figures 6 and 7 are sectional detail views of construction adapted for application to the helical groove structure.

In the drawings in which like characters of reference designate corresponding parts throughout the several views, A is a hot air furnace of ordinary construction, burning any of the usual fuels—wood, coal, gas or oil, as may be desired, B designating the casing thereof, C the dome, and D the hot air pipes. 1 designates the humidifier as a whole, and, as shown in Figs. 1 and 2, which is the preferred form, the same comprises a 65 hollow, conical-shaped metal case having a smooth interior and a grooved exterior surface presenting a spiral groove 2 leading downward from the central pin 3 to the lowermost point 4 where it ends in a collar 22 which receives therein an overflow pipe 5 which may be directed to a sewer or any 70 convenient receptacle.

The case 1 may be formed of cast metal, 75 particularly if made in the preferred form here shown in Figs. 1, 2, 6 and 7, and rests within the hot air chamber 6 upon the top of the dome C which is usually curved whereby the cone 1 very readily adapts itself to the intended position and use. From the cup 7 a feed pipe 8 leads through the casing B and terminates in an inverted cup piece 9 which is positioned detachably over the pin 3, and has a lateral opening 10 for the reception of the said pipe 8. This construction, it will be noted, serves to make possible 85 the rotation of the casing 1 for adjusting the position of the pipe 5 without interfering in any way with the connection with the pipe 8.

The walls of the cone 1 are perforated at 90 a plurality of points 11 to provide for air 100

circulation, and thus to increase the amount of evaporation from the liquid grooves. The cup 7 may also be provided with a special construction for sealing the water or other liquid flowing into said cup from entrance of outside air and dust into the chamber 6. The structure illustrated in Fig. 5 may be used for this purpose, and consists of a metal cup piece 12 having a central cylindrical space 13 opening outward into a frusto-conical opening 14 for receiving therein the lower and smaller end of the cup piece 7 as shown. The pipe 8 enters the said central space through a lateral opening 15. Within the said cup 7 is placed a concave member 16 which has an uneven edge, such as notches 17, to permit the liquid to flow down into the cup from the dropper 18, a needle valve 19 being provided in a pipe of liquid supply 21, such as the usual city mains for example, or an elevated tank, an ordinary shut-off valve 20 being provided to make easy the entire stoppage of liquid flow, when for any reason it is desired, as 25 in making repairs.

While the groove 2 which is arranged for spiral or helical arrangement on the exterior of the cone 1, may have a smooth bottom for the flow of the liquid therein, I have devised such groove with a series of sockets and protuberances therein which serve the double purpose of increasing the surface of liquid exposed to the warm air causing evaporation, thus increasing the latter, and 30 also present small obstacles to the continuous flow of the liquid in the groove and thus by hindering the said flow permit longer action of the hot air from the furnace pot thereon for a given length of groove. These 40 special details are illustrated on an enlarged scale in Figs. 6 and 7, and comprise sockets 27 of which I may use a large number, all being of course filled with the liquid as the latter flows along the groove 2, the heated cone 45 1 serving to cause heated liquid at the bottom of these sockets to rise to the surface of the liquid stream and both increasing evaporation from the surface but also serving to hinder somewhat the onward flow of 50 said stream. Also protuberances 28 are provided for the bottom of these grooves, their walls being thin, as shown particularly in Fig. 7, and having small channels or apertures 29 leading from inner space of the cone 55 up to and above the bottom of the groove. This structure provides a very effective heat surface for further evaporating the liquid in the stream flowing along the groove and thus increasing the speed of evaporation. 60 These sockets and protuberances 27 and 28 may alternate in a single coil of the groove 2, or parts 27 may be used in alternate coils with parts 28 provided in the others. It is immaterial from the patent 65 standpoint how these details are used, but I

intend to use a plurality of them on each coil, in either form of humidifier disclosed herein.

In Figs. 3 and 4 I have illustrated a modified form of humidifier which has its own peculiar advantages for certain uses and conditions. It is comprised of separated coils of open pipes forming grooves 23 therein, the pin 3 being used substantially as in the preferred form, and the lower or base end of the coil entering a lateral opening 25 in a block 24 which has an opening 26 to receive the pipe 5 which is used as in the preferred form. This modified form will ordinarily be made of sheet metal, the apertures 28 being punched up to the form made use of in the first form, and the sockets 27 formed in the same manner though by pressure from above. Fig. 4 shows suggestive location of such apertures and sockets, though they may be greatly increased in number.

In use, the cone device 1 is positioned on the dome 6 of the fire chamber, the pipe 5 being attached to the lower end or collar 22, pipe 8 being inserted through casing wall and cup 9 positioned on pin 3. The valve 19 is then adjusted for dropping water or other liquid at a speed approximately permitting the liquid to be evaporated from groove 2 by the time the residue could reach the collar 22. The parts may easily be cleaned, the cup parts 7 and 16 being readily detached and separated when necessary, and the humidifier itself may be wholly removed from the fire chamber for the same purpose.

The form of device shown in Figs. 3 and 4 requires no apertures as 11 to make entrance of hot air from within the cone outward to the main hot air chamber. Very perfect circulation is attained between the said chamber and the interior of the cone between the various spirals of this coil, since all are separated from each other. In this modified form, however, it is expedient to rest its large base upon the upper surface of the furnace dome, and to terminate the highest point of the coil in a pin 3 and connect the cup 9 thereon, as in the other form.

It will be apparent that I have devised a novel and useful humidifying device which is comparatively inexpensive, and yet serves when fitted with connections to inflow and outflow pipes connecting with proper sources, to make the air moist as it is about to enter the various rooms to be heated, that it embodies the features of advantage enumerated as desirable in the statement of the objects of the invention and the above description, and while I have, in the present instance, shown and described a limited number of embodiments thereof which will give in practice satisfactory and reliable results, it is to be understood that the same is susceptible of further modification in various

particulars without departing from the spirit or scope of the invention or sacrificing any of its advantages.

What I claim as new and desire to secure

5 by Letters Patent, is,—

1. The combination with the hot air chamber and dome of a hot air furnace, of a humidifier comprising a hollow conical casing seated removably on the top of said dome with its apex uppermost and terminating in a pin, an overflow pipe leading from the base of the cone to a point outside the chamber, an inverted cup adapted to enclose said pin and an inflow pipe leading from an 10 outside source of liquid supply and terminating within said chamber in said cup.
2. The combination with the hot air chamber and dome of a hot air furnace, of a humidifier comprising a cone-shaped support 20 having a helical groove on its external surface and opening outward from the support and serving to hold liquid therein, the base of said support being circular and adapted to rest removably on the said dome 25 and the apex thereof terminating in a vertical pin, inverted cup means adapted to fit over said pin, and in-flow pipe means entering the hot air chamber through the casing wall and having means for detachably connecting with said cup means.

3. The combination with the hot air chamber and dome of a hot air furnace, of a humidifier comprising a hollow cone-shaped casing seated removably on the top 35 of the said dome with its apex uppermost and terminating in a vertical pin, there being a helical groove leading from said apex downward about the exterior of the said hollow casing and terminating below in a connecting device at the base of the cone, an overflow pipe having the inner end inserted within said connection and directed outward through the wall of the chamber, an inflow pipe leading from an outer source 40 of supply of liquid to be evaporated and terminating within the said hot air chamber, and an inverted cup secured to said inflow pipe and adapted to fit removably over the said pin.

4. A humidifier for furnaces comprising a support having an external groove terminating at its lowest point in a connector member, a vertical pin on said support at its highest point from which said groove leads downward, and an inverted cup member 55 adapted to removably rest on said pin and having an aperture to receive a supply pipe therein.

5. A humidifier for hot air furnaces comprising a hollow cone-shaped, apertured case having a vertical pin at its apex and an open base and a helical groove in its external surface leading downward from said pin and winding about the said case and terminating at its base, a hollow connecting

member in which the lower end of the said groove ends, an inverted cup-shaped device adapted to fit over said pin, a supply pipe adapted to empty into said cup and an overflow pipe leading outward from said connector. 70

6. A humidifier for furnaces comprising a support having a vertical pin at its highest point, a plurality of ports in its side walls and a hollow connecting member at its base, there being an external helical groove on the outer surface of said support leading downward from said pin and terminating in said connector, an inverted cup member adapted to fit over said pin and having a lateral aperture therein, a supply pipe adapted to empty into said cup and an overflow pipe leading outward from said connector. 75

7. A humidifier for furnaces comprising a support having an external groove terminating at its lowest point in a connector member, hollow protuberances rising upward from the floor of said groove into the latter, a vertical pin on said support at its highest point from which said groove leads downward, and an inverted cup member adapted to removably rest on said pin and having an aperture to receive a supply pipe 90 therein. 95

8. A humidifier for furnaces comprising a support having an external groove terminating at its lowest point in a connector member, there being a series of spaced sockets or depressions in the floor of said 100 groove, a vertical pin on said support at its highest point from which said groove leads downward, and an inverted cup member adapted to removably rest on said pin and having an aperture to receive a supply 105 pipe therein.

9. A humidifier for furnaces comprising a support having an external groove terminating at its lowest point in a connector member, the floor of said groove having a 110 series of spaced depressions therein and a series of spaced hollow protuberances rising upward therefrom into the groove, the depressions alternating with the protuberances, a vertical pin on said support at its highest point from which said groove leads downward, and an inverted cup member adapted to removably rest on said pin and having an aperture to receive a supply pipe therein. 115

10. A humidifier for furnaces comprising a support having an external groove terminating at its lowest point in a connector member, hollow protuberances rising upward from the floor of said groove into the latter, there being channels or apertures 120 leading from the inner space within the protuberances through the walls of said support to the interior of the latter, a vertical pin on said support at its highest point from which said groove leads downward, and an 125

130

inverted cup member adapted to removably rest on said pin and having an aperture to receive a supply pipe therein.

11. A humidifier for furnaces comprising
5 a hollow, cone-shaped device including
therein an helical groove terminating at its
lowest point in a connector member, hollow
protuberances rising upward from the floor
of said groove into the latter, a vertical pin
10 at the apex of said device from which said
groove leads downward, and an inverted cup
member adapted to removably rest on said
pin and having an aperture to receive a
supply pipe therein.
12. A humidifier for furnaces comprising
a hollow, cone-shaped device including there-
in an helical groove terminating at its low-
est point in a connector member, there be-
ing a series of spaced sockets or depressions
20 in the floor of said groove, a vertical pin at
the apex of said device from which said

groove leads downward, and an inverted cup
member adapted to removably rest on said
pin and having means for receiving a supply
pipe therein.

13. A humidifier for furnaces comprising
a hollow, cone-shaped, apertured case hav-
ing a vertical pin at its apex and an open
base and a helical groove in its external sur-
face leading downward from said pin and
winding about the said case and terminating
at its base, there being a series of spaced
30 sockets or depressions in the floor of said
groove, a hollow connecting member in
which the lower end of the said groove ends,
an inverted cup-shaped device adapted to
fit over said pin, a supply pipe adapted to
empty into said cup and an overflow pipe
leading outward from said connector.

In testimony whereof I hereunto affix my 40
signature.

HARRY M. NOBIS.
